UNITED STATES PATENT OFFICE.

JOHN WICKS, OF CHICAGO, ILLINOIS, ASSIGNOR TO AUTOMATIC ELECTRIC COMPANY,
OF CHICAGO, ILLINOIS, A CORPORATION OF ILLINOIS.

AUTOMATIC TELEPHONE SYSTEM.

Application filed October 23, 1918. Serial No. 259,323.

To all whom it may concern:

Be it known that I, JOHN WICKS, a citizen of the United States of America, and a resident of Chicago, in the county of Cook and State of Illinois, have invented certain new and useful Improvements in Automatic Telephone Systems, of which the following is a specification.

My invention relates in general to automatic telephone systems and more specifically to an improved trunking arrangement for use in calls between exchanges, and improved switching and repeating mechanism for controlling automatic switches over two way trunk lines.

Among the objects of my invention are to provide a repeater and a selector repeater combined which function correctly when seized by a regular selector and thus the equipment is standardized so that it is not necessary to provide special selectors when calling to a repeater and over a trunk line between exchanges. These repeaters and selector repeaters are therefore controlled over a loop circuit in a standard way but may in turn transmit impulses over composite or other similar circuits in a manner to be pointed out. These and other objects of my invention including improved methods of supervision will be pointed out more in detail later.

Referring to the drawings, Figs. 1, 2, 3, 4 and 5 when placed end to end with Fig. 1 at the left show the various switches and circuits which are used to establish a connection from a calling substation A, Fig. 1 to a called substation B, Fig. 5; while Fig. 6 shows equipment which may be used by an operator in connection with the equipment of Figs. 2 to 5, inclusive, in establishing a similar connection from the substation A' to the substation B.

In Fig. 1 there is shown a substation A of well known 2 wire type having a line switch C individual thereto, which line switch is of standard rotary type and which operates when the receiver at substation A is removed to automatically select an idle trunk line leading to a selector D. The selector D is of well known Strowger two wire side switchless type of selector which responds to the calling device impulses to elect a group of trunk lines and then automatically selects a trunk line in the elected group which in this case is shown as leading to a

repeater E associated with a trunk line to a distant exchange.

This repeater E is then operated over two sides of the line by the calling device at substation A to in turn transmit impulses over a composite circuit superimposed on the trunk line in Figure 3 to a combined selector and repeater F, Figure 4.

The selector repeater in Fig. 4 operates in this instance as a regular selector to seize an idle trunk line extending to a connector H, Fig. 5, which is of standard type, and which is then operated by repeated impulses to find a called line such as that of substation B.

The operator referred to in connection with Fig. 6 may be a toll operator, paystation operator, complaint and information operator, or any other kind of operator such as is usually found in automatic exchanges. These operators according to well understood practice are provided with outgoing trunks over which they have access to the regular exchange trunking system and which may be used for connecting various kinds of lines terminating at their positions with called subscribers. These lines may be toll lines, paystation lines, or complaint and information trunks, etc., but for convenience a well known type of manual subscriber's line is shown, terminating in the jack J at an operator's position. The operator is provided with a plurality of cord circuits such as the cord circuit O, by means of which the line of station A' and other lines of the types mentioned may be connected to outgoing trunks such as the one terminating in the jack J'. The cord circuit O is of well known type such as is shown and described in the patent to Martin, #1,291,586, granted Jan. 14, 1919. The selector D', in which the outgoing trunk extending from jack J' terminates, is similar to selector D, Fig. 1.

I will now describe the operations in detail when a subscriber at substation A initiates a call.

When the receiver is removed, a circuit is closed from battery through slow relay 2, over the line to and through substation A, back over the other side of the line and to ground. Relay 2 energizes to close a series circuit from ground through springs 3, relay 4, and magnet 5 to battery. At the same time, however, another circuit is closed at springs 6 extending from private wiper 7, 110

through springs 8 and 9, springs 6, springs 10, and magnet 5 to battery. Now if the trunk line, on which the wipers of the switch C is resting, is busy, a ground will be present on contact 13 which will therefore short circuit the high resistance relay 4 in the series circuit first traced and will cause magnet 5 to operate to step the wipers of switch C over busy contacts until an idle trunk is found at which time, relay 5 is no longer short circuited and energizes to cut the line circuit through to first selector D and disconnect relay 2 and ground from the line circuit. Relay 4 is held energized by ground through springs 3 until a ground is fed back over the private from the switch ahead.

As soon as relay 4 energizes a circuit is completed for the line relay 14 of selector D over the line circuit to substation A in the usual manner. Relay 14 energizes relay 15, which in turn grounds the release trunk, and prepares a circuit for slow relay 16 and vertical magnet 17 in series. Relay 14 is now controlled by the calling device to fall back a predetermined number of times and thus complete the circuit of magnet 17 and relay 16 at springs 18 and 19. Magnet 17 operates to raise the wipers 20, 21 and 22 to some level of the bank. Relay 16 closes a circuit for rotary interrupter relay 23 which energizes and prepares a circuit for rotary magnet 24 at springs 25. When the impulses for this first digit cease and relay 16 falls back, a circuit is closed for rotary magnet 24 at springs 26 and 27 and springs 25. Magnet 24 upon energizing, opens the circuit of relay 23 at interrupter springs 28, thereby allowing relay 23 to fall back. Magnet 24 at the same time rotates the wipers 20, 21 and 22 onto the first set of contacts in the desired level. If this trunk line is busy a ground will be present on the private or test contact thereof and will immediately reenergize relay 23 from wiper 22 through springs 29 and 30, springs 28, off normal springs 31, and relay 23 to battery. Relay 23 will again close the circuit of magnet 24 and this operation will continue until an idle trunk line is found. When such a trunk is found there will be no ground to energize relay 23 and relay 32 which has heretofore been short circuited by the ground on the private wiper, energizes over a circuit from ground at relay 15, relay 32, springs 28, springs 31, and relay 23 to battery. Relay 32 being of high resistance does not permit relay 23 to energize.

Relay 32 upon energizing, disconnects the line relay 14 from the extended line circuit and cuts said line circuit through its front contacts to line wipers 20 and 21. A locking circuit is also closed for relay 32 which extends over the above traced circuit but will later get its ground from the switch ahead through wiper 22, and springs 29 and 33.

As soon as the line circuit is cut through

to the repeater E, and before the relay 15 falls back, a ground impulse is sent over the private wiper 22 through springs 34 and 35, springs 36 and 37, and through relay 38 to battery. Relay 38 upon energizing, prepares a locking circuit for itself at springs 39, and connects the line relay 40 across the line circuit and in series with the substation A. Relay 40 now energizes and closes a circuit for relay 41 at springs 42 and 43. Relay 41 upon energizing connects ground to the holding circuit of relay 38 through springs 62, 63 and 39 and on to the relay 32 of the selector, and also closes a circuit for the reversing relay 44, which relay 44 is however immediately cut off by the energization of relay 45 as will be explained. Relay 41 also prepares an impulsing circuit at springs 46 and 47 and prepares a circuit for relay 49 at springs 48. The impulsing circuit closed by the joint action of relays 40 and 41 extends from battery through the upper winding of relay 45, springs 50, springs 47 and 46, conductor 51, upper composite coil 52, trunk line conductor 53, coil 54, conductor 55, springs 56 and 57, springs 58 and 59, and upper winding of relay 60 to ground. Relays 45 and 60 energize over this circuit. Relay 45 opens the circuit of relay 44 at springs 64 before that relay has time to energize as has been pointed out. We now have the line relay 60 of the selector repeater F energized in series with the conductor 51 and the relay 45 through the contacts 50 of line relay 45 of the repeater E.

As the calling subscriber at A now operates his calling device for the next digit of the called number the relay 40 falls back a number of times to deliver impulses to relay 60 over the above circuit. During the operation of relay 40, relays 41 and 49 are both held energized by ground from spring 42. Relay 49 while energized, closes a low resistance shunt circuit about the winding of relay 45 at springs 65 through resistance 66 and opens another point in the circuit of relay 44 at springs 67. Each time springs 50 separate relay 60 falls back to close a circuit for magnet 68 and relay 69 in series. When relay 60 first energized it closed a circuit from ground through springs 70 and 71, springs 72 and 73, and relay 74 to battery. Relay 74 energizes to ground the normal private through springs 75 and 76; prepares a circuit for relay 69 and magnet 68 and closes the circuit of a high resistance polarizing winding of coil 77. Each time the magnet 68 energizes the wipers 78, 79 and 80 are raised one step until they stand before a desired group of trunk lines. Relay 69 upon energizing and after the shaft has taken its first vertical step closes a circuit from ground through springs 75 and 76, springs 81 and 82, springs 83, and rotary interrupter relay 84 to battery. Relay 84

upon energizing, prepares a circuit for rotary magnet 85 at springs 86. When relay 69 falls back after this digit the circuit of magnet 85 is closed through springs 5 75 and 76, springs 81 and 87, and springs 86. Magnet 85 therefore operates to step the wipers 78, 79 and 80 onto the first set of contacts of the elected level. Relay 84 also closed a locking circuit for itself from battery 10 through relay 84, springs 83, springs 88, springs 89, and springs 90 and 91 to ground. This circuit is opened by magnet 85 at springs 88. Now if the first trunk line is busy, ground at wiper 80 passes through springs 15 92, springs 88, springs 83, and relay 84, again energizing relay 84 and again energizing magnet 85. This operation continues until an idle trunk line is found, at which time no ground is present at wiper 80 and 20 relay 84 will not find ground when 85 falls back. At this time, relay 93, which has heretofore been shorted out, energizes over a circuit from ground through springs 75 and 76, relay 93, springs 88, springs 83, and relay 84 to battery. Relay 93 being 25 of high resistance, energizes but does not allow relay 84 to energize. Relay 93, upon energizing, disconnects the relay 69 from the control of line relay 60 and connects the 30 slow relay 94 in place thereof through springs 95 and 96, closes the line circuit at springs 97, disconnects the relay 98 from the line circuit, and connects the lower winding of polarized relay 77 in series with resistance 99, across the line circuit through springs 100 and 101 and springs 102 and 103. Relay 93 also connects the private wiper 80 through springs 104 to the holding circuit of relay 93. As soon as relay 35 40 93 energizes line relay 105 of the connector switch H (Fig. 5) energizes over a circuit from ground through its lower winding, springs 106' and 107, wiper 79, springs 97, winding of the repeating coil, springs 102 and 103, lower winding of relay 77, resistance 99, springs 100 and 101, upper winding of the repeating coil, springs 108, wiper 78, springs 109 and 110, and upper winding of relay 105 to battery. Relay 105 in turn 45 closes a circuit for relay 106, which supplies ground through springs 112, 113, and 114 to the release trunk and also prepares a circuit for relay 115 and vertical magnet 116 in series. 50

55 Each time the line relay 60 is deenergized in response to the next series of impulses, the springs 108 are allowed to open their contacts to repeat the impulses to relay 105. At the same time relay 60 closes a circuit 60 from ground through back contact of spring 70, front contacts of relay 74, springs 96 and 95, and relay 94 to battery. Relay 94 closes a more direct impulsive circuit for the line relay 105 through the springs 117 65 so that the winding of relay 77 and resistance 99 are not included therein. Relay 105 of the connector now controls magnet 116 to step the wipers 118, 119 and 120 to some level of the bank in the usual manner. Relay 115 upon falling back prepares the 70 circuit of rotary magnet 121 and slow relay 122 in multiple, the off normal contacts O N having operated to close their alternate contacts in the meanwhile. 75

The next operation of relay 105, therefore, through the medium of line relay 60, closes this circuit of magnet 121 and relay 122, and magnet 121 is operated a predetermined number of steps to put the wipers 118, 119 and 120 into connection with the called subscriber's line. If the called line be busy then before relay 122 falls back, a circuit is closed from ground on the private wiper through front contacts of relay 122 and busy relay 123 to battery. Relay 123 applies busy tone to the calling line in the usual manner. If the called line is idle then as soon as relay 122 falls back a circuit is closed for the cut off relay of the called man's line switch, through wiper 120, back 80 contact of relay 122, lower winding of relay 124, and ground at relay 106. Relay 124 operates to cut the line circuit through to the called man and locks itself through its upper winding. The called subscriber 85 is then signalled in the usual manner by ringing machine R and when the called man answers, relay 125 energizes to cut off the signalling current and connect the called line to the windings of back bridge relay 126. Relay 126 now energizes in series with the called line and reverses the connections of the line relay 105 with regard to the line conductors, thereby reversing the direction 90 of the current flow in the lower winding of relay 77 of the repeater F. Relay 77 being electropolarized now energizes for the first time, as currents in both windings now assist each other. The results of the energization 95 of relay 77 are as follows: A circuit is closed for the lower winding of relay 60 to hold it energized, the conductor 55 is switched from the upper winding relay 60 to the upper winding of relay 127. By this 100 operation the conductor 55 is switched from ground to battery at the repeater F and therefore the relay 45 which is also connected to battery at the other end of conductor 51 is deenergized and closes the 105 springs 64. When springs 64 close a circuit is completed for relay 44 which energizes 110 to reverse the connections of the line relay 40 with regard to the calling line. This reversal of current may be used to operate a meter when the call is from a subscriber's line direct or may give supervision to an operator in case the switch E had been seized by an operator, as will be pointed out more fully hereinafter. It will be seen that this 115 reversal of current is relayed or repeated on 120

125 130

from the called to the calling end of the trunk line over the composite circuit. The two subscribers may now converse over the heavy conductors shown.

Should the calling subscriber hang up his receiver first, the line relay 40 of the repeater E deenergizes and allows relay 41 to deenergize. Relay 41 removes ground from the holding circuits of the switches C and D which release in the usual manner. Also relay 41 switches the conductor 51, which was formerly connected through relay 45 to battery, through the back contact of spring 46 and springs 128 and 129 to ground through upper winding of relays 130. Relays 130 and 127 energize over this circuit. Relay 127 of selector repeater F upon energizing, opens the contact of springs 72 and 73 in the circuit of relay 74 which relay 74 falls back and closes the circuit of release magnet 131 which releases the switch and opens the off normal springs. Relay 77 will of course fall back as soon as the wipers leave their contacts and relay 60 is therefore again connected to the conductor 55 in series with relay 130 of the repeater E. Relays 130 and 60 being both grounded, relay 130 falls back and relay 60 will not energize. The deenergization of relay 130 of the repeater E results in the restoration of the associated circuits to their normal condition. When the called man hangs up the connector H will be released. In case the called man hangs up first, the circuits are restored to the condition existing just prior to the answering of the called man, except that the ring cut-off relay 125 of the connector H of course remains locked up. In this case, when the calling subscriber hangs up his receiver, line relay 40 of the repeater E falls back and opens the circuit of the line relay 60 of the repeater F, which in turn falls back and opens the circuit of line relay 105 of the connector H. The release of the switches C and D, Fig. 1, and the restoration to normal of the circuits of the repeater E take place responsive to the deenergization of line relay 40, and the release of the switches F and H takes place responsive to the deenergization of the relays 60 and 105.

It will thus be seen that the impulsing, releasing and reversal of battery for supervision are all controlled over the single conductor including conductor 51 at one end and 55 at the other.

As the trunk circuit shown is two way, I will now describe the operation of the invention when a subscriber in the exchange with B operates a selector to seize the normals 200, 201 and 202 of the selector repeater F to call some subscriber in the exchange with A.

When a selector such as D (Fig. 1) seizes the contacts associated with the normals

200, 201 and 202 a preliminary ground is supplied to conductor 202 from the selector as usual which flows through the high resistance upper winding of the electropolarized relay 77 to battery. Relay 77 does not energize at this time owing to the high resistance of its upper winding. As soon as the line is cut through by the selector, the relay 98 is energized in series with the calling line circuit and operates to energize relay 204 through springs 205 and 206, and to close springs 207. Relay 204 connects ground through springs 208 and 209, off normal springs 210, spring 76 and its back contact, and back to conductor 202 thus supplying a holding ground to the selector or other switches used to seize the selector repeater; prepares a circuit for relay 94 at springs 211, and switches conductor 55 from the upper winding of relay 60 to the lower winding of relay 127 through spring 56 and its front contact, lower winding of said relay, springs 207, and resistance 212 to battery. The impulsing circuit may now be traced from spring 56 over conductor 55, coil 54, trunk conductor 53, coil 52, conductor 51, spring 46 and its back contact, springs 128 and 129, and upper winding of relay 130 to ground. Relays 130 and 127 are energized over this circuit and relay 127 at armature 233 opens the circuit of reversing relay 203, which circuit was initially closed upon the application of the ground potential to conductor 202 by the seizing selector through armature 76 and its back contact, off normal contacts 210, upper contacts of relay 94, and the back contact and armature 233, thereby preventing relay 203 from operating at this time. Relay 130 upon energizing closes a circuit from ground through spring 62 and its back contact, springs 213 and 214 and relay 215 to battery. Relay 215 energizes to ground the private contact in the bank of selectors such as D through spring 34 and its front contact, grounds the high resistance polarizing winding of the coil 216, prepares a circuit for slow relay 49, and closes a bridge across the conductors 217 and 218 which will in this case lead to a selector such as D, Fig. 1. The line relay of this selector will therefore be energized as was the line relay 14 of selector D except that the energizing circuit, instead of passing through a subscriber's line circuit will in this case pass from conductor 217, through springs 220 of relay 130, upper winding of the repeating coil, springs 221 and 222, resistance 223, upper winding of relay 216, springs 224 and 225, lower winding of the repeating coil, springs 226 of relay 215, and springs 227 back to conductor 218.

When the calling subscriber now operates his dial for the next digit the circuit of relay 98 at the selector repeater F is broken

a number of times. Each time relay 98 de-energizes it opens the springs 207 and also operates spring 205 to close the circuit of relay 94 which remains energized during the series of impulses. Relay 94 opens a point in the circuit of reversing relay 203, and also closes a short circuit around the winding of relay 127 in the dialing circuit thus causing the impulses to pass through springs 207, springs 228 and spring 56 and its front contact thus cutting down the resistance in the dialing circuit to relay 130. Each time springs 207 separate, relay 130 at the repeater E falls back and in the same manner keeps relay 49 energized during the transmission of impulses, over the circuit prepared by relay 215. Relay 49 closes a short circuit about the upper winding of relay 216 and resistance 223 in series with the line relay of the selector being operated so that each time relay 130 deenergizes the line relay of said selector is controlled over a circuit from conductor 217 through springs 220, springs 229, springs 227, and conductor 218. The line relay of the selector will therefore be operated to seize a connector such as that shown at H which will in turn be operated in the same manner to seize the line of a called subscriber. It will be understood that any desired switches may be connected to conductors 217 and 218, depending upon the size of the exchange. When the called subscriber answers after being signalled a back bridge relay such as 126, Fig. 5, will be operated to reverse the current flow in conductors 217 and 218 and therefore through the upper winding of relay 216, which will energize with both its windings assisting each other. Relay 216 closes a circuit from ground through springs 230, and lower winding of relay 232 to battery. Relay 232 upon energizing switches the conductor 51 of the impulsing circuit from the winding of relay 130 and ground, through the winding of relay 45 to battery.

As the impulsing circuit is now connected to battery at both ends as in the case of the call previously described, neither of the relays 45 or 127 will be energized now and although relay 130 is cut off from its original energizing circuit, it is held energized from ground through springs 231 of relay 216 and lower winding of said relay 130. Relay 127 upon deenergizing closes the springs 233 in the circuit of reversing relay 203. Relay 203 upon energizing, reverses the connections of the line or repeating relay 98 with regard to line conductors 200 and 201, thereby reversing the direction of current flow therein.

Conversation may now be carried on over the heavy conductors shown. Should the calling subscriber restore his receiver first, the energizing circuit of relay 98 will be broken and this relay 98 will open the cord circuit O, for example, and then oper-

85 springs 207 and also open the circuit of relay 204. Relay 204, upon deenergizing, opens the circuit of relay 203 and of upper winding of relay 77, and closes springs 56 and 57, the impulsing circuit is thereby connected through springs 56 and 57 and springs 58 70 and 59 through relay 60 to ground.

75 The opening of springs 208 and 209 of relay 204 removes ground from conductor 202 and allows the release of the switches held thereover. Relays 60 and 45 now energize over the impulsing circuit. Relay 45 of repeater E upon energizing opens the springs 234 in the circuit of lower holding winding of relay 130. Relay 130, upon de-energizing, opens the springs 220 which control the bridge across conductors 217 and 218. When this bridge is opened the switches controlled thereover will release and relay 216 will release and restore all relays to normal.

80 Now suppose the called subscriber is the first to restore his receiver when conversation is completed, then the back bridge relay of the connector switch will be deenergized to restore the current to normal in the lower winding of relay 216 of repeater E at 90 springs 230, also restores relay 232 to again include relay 130 in place of relay 45 in the impulsing circuit. Now when the calling subscriber hangs up the connection is entirely restored to normal by deenergization of 95 relay 98 and the resultant deenergization of relay 204, which in this case connects conductor 55 to relay 60 and ground, thereby de-energizing relay 130 of repeater E and opening the bridge of conductors 217 and 218 100 at springs 220. It will therefore be seen that a connection may be extended in either direction over the superimposed circuit which includes the talking conductors of one side of the two trunk lines X and Y (Fig. 3) 105 and that the connection either way is set up over the impulsing circuit including the conductors 51, 53 and 55 of one of said trunk lines. Also this conductor is used for controlling the release of the connection by switching said conductor either to ground or battery at either end and also for supervision or metering in the same manner.

110 Having explained fully the process of establishing connection when the calling subscribers are automatic subscribers, I will now point out briefly how one of the lines terminating at the operator's position is extended to a called line.

115 Supposing that the subscriber at substation A', Fig. 6, wishes to obtain connection with the subscriber at substation B, Fig. 5, when the receiver is removed to initiate the call, the line relay 301 is energized, lighting the line lamp L. The operator responds by plugging into the jack J with the answering plug of an idle one of her cord circuits, 120 cord circuit O, for example, and then oper-

ates her listening key K in order to converse with the calling subscriber and find out what number he wants.

When the plug is inserted in the jack the sleeve relay 303 and the cut off relay 302 are energized in series, and the latter relay disconnects line relay 301 to put out the line lamp. Relay 303, upon energizing, closes a point in the circuits of lamps L' and L² but neither lamp is lighted at this time. The circuit of lamp L' is open at a contact of relay 304, which has just been energized over the calling line, while the circuit of lamp L² is open at a contact of the polar relay 306.

As soon as the operator obtains the necessary information as to the desired number she will plug into an idle outgoing trunk jack, jack J', for example, with the calling plug of cord circuit O, and will operate the calling device key K'. By these operations the connection is extended to the trunk line which terminates in the selector D' and the calling device S is connected in bridge of the two line conductors of the trunk line. Accordingly the line and release relays 320 and 321 are energized and the selector is prepared for operation in the usual manner.

The operator will now manipulate her calling device in accordance with the first digit of the desired number, whereupon selector D' is operated as was described in connection with the selector D, Fig. 1, to establish connection with the trunk line extending to and terminating in the repeater E, Fig. 2. Succeeding operations of the calling device in accordance with the remaining digits now serve to control the repeater E, the selector repeater F, Fig. 4, and the connector H, Fig. 5, to complete the connection to the line of substation B. When the last digit is called the operator will restore the key K'. By this operation the polar relay 306 is substituted for the calling device S in bridge of the trunk line extending to the selector D', and the said relay is accordingly energized in series with the line relay 40 of repeater E. The direction of current flow at this time is such that the armature of relay 306 is actuated to close the circuit of lamp L² and the lamp is lighted.

The operation of the apparatus shown in Figs. 2, 4, and 5 has been fully set forth before and it will therefore be unnecessary to again go into these operations in detail. It will be sufficient to point out that when the called subscriber answers, conductor 55, Figs. 3 and 4, is switched from ground to battery at selector repeater F, causing relay 45 of the repeater E to fall back. Upon de-energizing, relay 45 closes a circuit for the reversing relay 44 at springs 64, and relay 44, upon energizing, transposes the incoming trunk conductors as regards their connec-

tions to the windings of the line relay 40. The direction of current flow in the winding of the polar relay 306 at the cord circuit O is accordingly reversed and the polar relay armature is operated to open the circuit of lamp L². This extinguishes the lamp and indicates to the operator that the called subscriber has answered.

The required connection has now been established and conversation may proceed as usual. When the subscribers are through talking they will replace their receivers and disconnect signals will be given to the operator by the lighting of lamps L' and L². The circuit of lamp L' is closed by relay 304 on deenergizing, while the circuit of lamp L² is closed by polar relay 306 responsive to the reversal of the direction of current flow in its winding back to normal. When the operator perceives the disconnect signals she will pull down the connection. By this operation the polar relay 306 is disconnected from in bridge of the outgoing trunk and the circuit of the line relay 40 of the repeater E is broken, the same as was described in the case of the connection which was established by the subscriber at the automatic substation A. The release of the switches then follows exactly as has been previously described. It will be understood of course that the operator can bring about the release of the connection at any time either before or after the called subscriber has replaced his receiver, simply by removing the plug from jack J', the release in either case being brought about the same as in an automatic connection.

Having fully described and ascertained the features and aspects of my invention, what I consider to be new and desire to have protected by Letters Patent will be pointed out in the appended claims.

What I claim as my invention is:

1. In a telephone system, a trunk line, an automatic switch in which said trunk line terminates at the near end, an operating circuit for said switch superimposed on said trunk line and normally connected to the same pole of battery at both ends, means for temporarily connecting said circuit at the distant end thereof to the opposite pole of battery to operate said switch, means for also connecting said circuit at the near end thereof to the opposite pole of battery after said switch has been operated, and release means in said switch responsive when the said circuit is restored to normal condition at the distant end.

2. In a telephone system, a pair of trunk lines, a phantom circuit superimposed on the conductors of said trunk lines, a composite circuit superimposed on a conductor of one of said trunk lines, a switch at each end of said phantom circuit for extending connections therefrom, a relay in each end of said composite circuit connected to

- the same pole of battery, means for connecting either end of said composite circuit to the opposite pole of battery to control the relay on the opposite end to operate its associated switch, and means for switching said opposite end to the other pole of battery when a called subscriber answers.
3. In a telephone system, a pair of trunk lines, a phantom circuit superimposed on the conductors of said trunk lines, an automatic switch at each end of said circuit for extending connections therefrom to called subscribers, a common operating circuit for said switch normally grounded at each end through an operating magnet of the associated switch, means for connecting either end of said circuit to battery to control the switch at the opposite end thereof to extend a connection to a called subscriber, means controlled by the called subscriber for switching said circuit to battery at the said opposite end to reverse the battery current in the calling line, and means controlled by the calling subscriber for connecting said circuit to ground again at the near end to again cause a flow of current in said circuit to release the switch at the opposite end thereof.
4. In a telephone system, a two-way trunk line having a switch at each end thereof for extending connections therefrom to called lines, a common operating circuit for said switches, means for causing current to flow in one direction over said circuit to operate one of said switches, and in the other direction to operate the other switch, means for cutting off the flow of current in said circuit when a called subscriber answers, and means for causing current to flow in a direction opposite to that used to operate a switch to release the same.
5. In a telephone system, a two-way trunk line, having a selector repeater at one end and a repeater at the other, means for seizing either end of said trunk line and transmitting impulses over two sides thereof in series, and means in the seized end for repeating said impulses over a single conductor to the opposite end thereof to extend a connection therefrom, and means controlled by the response of a called subscriber for controlling said conductor to reverse the flow of current in the seized end of said trunk, and means for causing a flow of current over said conductor in the opposite direction to that used to extend the connection, to release the connection.
6. In a telephone system, a phantom talking circuit superimposed on two physical talking circuits between two exchanges, a composite circuit superimposed on one of said physical circuits, means at either end of said phantom circuit for receiving two wire impulses and repeating the same over one leg of said composite circuit, and means at either end responsive to impulses over said composite circuit to operate switches over two sides of a trunk line in series to complete a talking connection from said phantom.
7. In a telephone system, a phantom circuit between two exchanges, a composite operating circuit superimposed on one of the physicals of said phantom over which connections may be extended from said phantom in either direction, and means controlled solely over said composite circuit for operating and releasing two wire switches in either exchange, for reversing the battery to a calling subscriber, and for controlling the supervision of an operator in case an operator is extending the connection.
8. In a telephone system, a trunk line connecting two exchanges, a switch control circuit including a conductor of said trunk line, means whereby a calling subscriber in one exchange can insert a battery in said circuit to cause a flow of current therein, means for then interrupting the circuit, automatic switches in the second exchange responsive to the interruptions for connecting with a called line, and means operated when the called subscriber answers for inserting a second battery in said circuit in opposition to said first battery, thereby stopping the flow of current during conversation.
9. In a telephone system, a trunk line connecting two exchanges, a switch control circuit including a conductor of said trunk line, means whereby a calling subscriber in one exchange can insert a battery in said circuit to cause a flow of current therein, means for then interrupting the circuit, automatic switches in the second exchange responsive to the interruptions for connecting with a called line, means operated when the called subscriber answers for inserting a second battery in said circuit in opposition to said first battery, thereby stopping the flow of current during conversation, means controlled by the calling subscriber for closing said circuit over a path excluding said first battery to establish a current flow from said second battery, and means responsive to current from said second battery for then causing the release of said switches.
10. In a telephone system, a trunk line, a normally closed switch control circuit including a conductor of said trunk line and a ground return, means whereby a calling subscriber at one end of said trunk can establish a flow of current in said circuit and thereafter produce interruptions therein, automatic switches at the other end of said trunk line responsive to said interruptions for connecting with a called line, and means operated upon the response of the called subscriber for closing said circuit over a new path to prevent the flow of current therein during conversation.
11. In a telephone system, a trunk line, a

normally closed switch control circuit including a conductor of said trunk line and a ground return, means whereby a calling subscriber at one end of said trunk can establish 5 a flow of current in said circuit and thereafter produce interruptions therein, automatic switches at the other end of said trunk line responsive to said interruptions for connecting with a called line, means operated 10 upon the response of the called subscriber for closing said circuit over a new path to prevent the flow of current therein during conversation, and means responsive to the restoration of said circuit to normal condition 15 at the calling subscriber's end of the trunk for releasing said switches.

12. In a telephone system, two exchanges and an interconnecting trunk line, means whereby a calling subscriber in the first exchange can establish a current flow over a 20 normally closed switch control circuit superimposed on said trunk line, automatic switches in the second exchange responsive to interruptions produced in said circuit for extending a connection to a called line, means operated upon the response of the called subscriber for preventing the flow of current over said closed control circuit during conversation, and a relay held energized 25 over the called line to prevent the release of said switches after the current flow over said control circuit has ceased.

13. In a telephone system, two exchanges and an interconnecting trunk line, means whereby a calling subscriber in the first exchange can establish a current flow over a 30 normally closed switch control circuit superimposed on said trunk line, automatic switches in the second exchange responsive to interruptions produced in said circuit for extending a connection to a called line, means operated upon the response of the called subscriber for preventing the flow of current over said closed control circuit during conversation, the current flow being re-established when the called subscriber hangs 35 up, and means controlled by the calling subscriber for releasing said switches.

14. In a telephone system, two exchanges and an interconnecting trunk line, means whereby a calling subscriber in the first exchange can establish a current flow over a normally closed switch control circuit superimposed on said trunk line, automatic 40 switches in the second exchange responsive to interruptions produced in said circuit for extending a connection to a called line, means operated upon the response of the called subscriber for preventing the flow of current over said closed control circuit during conversation, and means operable by the calling subscriber before the called subscriber hangs up for again setting up a current flow over said closed control circuit to 45 release the said switches.

15. In a telephone system, two exchanges and an interconnecting trunk line, means whereby a calling subscriber in the first exchange can establish a current flow over a 50 normally closed switch control circuit including the conductor of said trunk line and a ground return, automatic switches in the second exchange responsive to interruptions produced in said circuit for extending a connection to a called line, means in the second 55 exchange controlled by the called subscriber for stopping the flow of current in said closed control circuit during conversation, means controlled by the called subscriber for preventing the release of said switches responsive to the cessation of current flow in said control circuit, means in the first exchange controlled by the calling subscriber for reestablishing a current flow in said closed control circuit before the called subscriber hangs up, and means in the second exchange responsive to the reestablished current flow for releasing said switches. 60

16. In a telephone system two exchanges and an interconnecting trunk line, means whereby an operator in one exchange can connect with said trunk line and establish a current flow over a normally closed switch control circuit superimposed on said trunk line, means for then momentarily interrupting the circuit at the first exchange, automatic switches at the second exchange responsive to the interruptions for connecting with a called line, and means operated upon the response of the called subscriber for stopping the current flow in said control circuit to give the operator a supervisory signal. 65

17. In a telephone system, two exchanges and an interconnecting trunk line, means whereby an operator in one exchange can connect with said trunk line and establish a current flow over a superimposed switch control circuit including one conductor of said trunk line and a ground return, means for then momentarily interrupting the circuit at the first exchange, automatic switches at the second exchange responsive to the interruptions for connecting with a called line, means operated upon the response of the called subscriber for preventing the flow of current over the control circuit during conversation, means responsive to the cessation of the current flow for giving the operator a supervisory signal, and a relay held energized over the called line to prevent the release of said switches after the current flow over said control circuit has ceased. 110

18. In a telephone system, two exchanges and an interconnecting trunk line, means whereby an operator in one exchange can connect with said trunk line and establish a current flow over a normally closed switch control circuit superimposed on said trunk line, means for then momentarily interrupt- 115 120 125 130

ing the circuit at the first exchange, automatic switches at the second exchange responsive to the interruptions for connecting with a called line, means operated upon the 5 response of the called subscriber for stopping the current flow in said control circuit to give the operator a supervisory signal, and means operated when the operator pulls down the connection for reestablishing a 10 flow of current in said control circuit to cause the release of said switches.

19. In a telephone system, a trunk line connecting two exchanges, a switch control circuit including a conductor of said trunk 15 line, a manual switchboard in the first exchange, means whereby an operator at said switchboard can insert a battery in said circuit to cause a flow of current therein, operator controlled means for then interrupting 20 said circuit, automatic switches in the second exchange responsive to the interruptions for connecting with a called line, means operated when the called subscriber answers for inserting a second battery in said circuit in 25 opposition to said first battery, thereby stopping the flow of current during conversation, and means responsive to the cessation of current flow for giving the operator a supervisory signal.

30 20. In a telephone system, a trunk line connecting two exchanges, a switch control circuit including a conductor of said trunk line, a manual switchboard in the first exchange, means whereby an operator at said 35 switchboard can insert a battery in said circuit to cause a flow of current therein, operator controlled means for then interrupting said circuit, automatic switches in the second exchange responsive to the interruptions for 40 connecting with a called line, means operated when the called subscriber answers for inserting a second battery in said circuit in opposition to said first battery, thereby stopping the flow of current during conversation, 45 means responsive to the cessation of current flow for giving the operator a supervisory signal, operator controlled means for closing said circuit over a path excluding said first battery to cause a current flow from 50 said second battery, and means responsive to current from said second battery for causing the release of said switches.

55 21. In a telephone system, two exchanges and an interconnecting trunk lead, automatic switches in the second exchange controlled from the first exchange for establishing a talking connection over said trunk line, the release of said switches after the connection is established being also controlled from the first exchange, first and second batteries in said first and second exchanges, respectively, means for supplying current to said trunk line from said first battery for controlling the operation of said switches, means for 60 connecting the second battery when the

connection is established, both batteries being connected to the trunk in opposition during conversation, and means for cutting out the first battery to cause a current flow from the second battery and release the connection. 70

22. In a telephone system, an automatic switch, a trunk line over which said switch may be controlled to operate and release the same, a grounded battery at each end of said 75 trunk, suitable circuits for connecting the ungrounded poles of said batteries to the trunk, the arrangement being such that whenever both batteries are connected to the trunk at the same time they are in opposition, and relays for closing said circuits at proper times to supply current from one of said batteries to said trunk for controlling the operation of said switch, and to supply current from the other of said batteries 80 to said trunk to control the release of said switch. 85

23. In a telephone system, a trunk line and a train of automatic switches for use by an operator in extending a connection to 90 a called line, a supervisory signal, a combination supervisory and switch control circuit including a conductor of said trunk line, a battery included in said circuit at the operator's end of the trunk line for supplying current to set said switches, a second battery at the other end of the trunk inserted in said circuit in opposition to said first battery when the called party responds, and means responsive to the resulting cessation 95 of current flow in said circuit for controlling said signal. 100

24. In a telephone system, a trunk circuit for connecting a calling and called line, an automatic switch at the called end of said trunk circuit for connecting with the called line, a device at the calling end of said trunk line responsive to the answering of the called party, a battery at the calling end of said trunk line 105 for supplying current over the trunk line to control the setting of said switch, a second battery at the called end of said trunk line substantially equal in voltage to said first battery, means controlled by the called party for connecting said second battery in opposition to said first battery to substantially prevent current flow over the trunk line from either battery, and means responsive to the cessation of current flow for controlling said device as set forth. 110

25. In a telephone system, two exchanges and an interconnecting trunk line, a switch control circuit, means in the first exchange for connecting with said trunk line and for establishing a flow of current in said circuit, means at the first exchange for then producing momentary interruptions in the current flow, automatic switches at the second exchange responsive to the interruptions for 125 130

- extending the trunk line to a called line, means controlled by the called party when he answers for stopping the flow of current in said circuit, and a supervisory relay in the first exchange responsive to the cessation of current flow in said circuit. 5
26. In a telephone system, two exchanges and an interconnecting trunk line, a switch control circuit, means in the first exchange for connecting with said trunk line and for establishing a flow of current in said circuit, means at the first exchange for then producing momentary interruptions in the current flow, automatic switches at the second exchange responsive to the interruptions for extending the trunk line to a called line, means controlled by the called party when he answers for stopping the flow of current in said circuit, a relay in the first exchange for controlling a supervisory signal, and means responsive to the cessation of current flow in said circuit for operating said relay. 10
27. In a telephone system, two exchanges and an interconnecting trunk line, a switch control circuit, means in the first exchange for connecting with said trunk line and for establishing a flow of current in said circuit, means at the first exchange for then producing momentary interruptions in the current flow, automatic switches at the second exchange responsive to the interruptions for extending the trunk line to a called line, means controlled by the called party when he answers for stopping the flow of current in said circuit, a supervisory relay in the first exchange responsive to the cessation of current flow in said circuit, means in the first exchange for re-establishing the flow of current in said circuit, and means responsive to the renewed current flow for releasing the connection. 15
28. In a telephone system, a circuit, means at one end of said circuit for setting up a flow of current therein and for subsequently producing momentary interruptions in the current flow, a switch at the distant end operated responsive to such interruptions, means at the distant end for stopping the flow of current in said circuit while maintaining the switch in operated position, signal controlling means at the near end responsive to the cessation of current flow, and means at the near end for again establishing the flow of current to release said switch. 20
29. In a telephone system, an automatic switch, means including a control circuit for said switch for operating the same to connect with a called line, and releasing means for said switch responsive either to the establishment or the cessation of current flow in said circuit depending on whether the called line is in answered or unanswered condition. 25
30. In a telephone system, a trunk line terminating in an impulse repeater, a first closed circuit including a conductor of said trunk line and a source of current, a second closed circuit including a source of current and extending from said repeater to a distant point, said repeater being responsive to a series of interruptions in the current flow in said first closed circuit to produce a series of interruptions in said second closed circuit, means at said distant point for stopping the current flow over said second closed circuit, and means in said repeater responsive to such cessation of current flow for reversing the direction of current flow in said first closed circuit. 30
31. In a telephone system, a trunk line extending to an automatic impulse repeater, a closed circuit including said trunk line and a source of current, a second closed circuit including a source of current and extending from said repeater to a distant point, said repeater being responsive to control over said first circuit to produce interruptions in the current flow in said second closed circuit, means at said distant point for interrupting the current flow over the associated closed circuit, and means in said repeater responsive to such cessation of current flow for reversing the direction of current flow in the first named closed circuit. 35
32. In a telephone system, an impulse repeater for producing a series of interruptions in the current flow through a closed circuit, means outside of said repeater for interrupting the current flow in said closed circuit, a trunk circuit incoming to said repeater, a relay for exercising a control over said trunk circuit, said relay being operated responsive to said outside interruption, and a slow acting relay in said repeater energized during the production of said series of interruptions to prevent the said operation of said relay. 40
33. In a telephone system, an impulse repeater for producing a series of interruptions in the current flow through a closed circuit, means outside of said repeater for interrupting the said current flow, a supervisory relay in said repeater operated responsive to said outside interruption, and a slow acting relay in said repeater energized during the production of the series of interruptions in the said closed circuit to prevent the said operation of said supervisory relay from taking place at such time. 45
34. In a telephone system, a trunk line terminating in an impulse repeater, a control relay in said repeater for controlling the current flow in said trunk line, means for extending a connection to said trunk line and for closing a circuit for said control relay, a conductor extending from said repeater to a distant point, means responsive to the said extension of the connection for setting up a current flow over said con- 50

ductor, a second relay in said repeater responsive to such current flow for opening the circuit of said control relay before the latter has had time to operate, and means at 5 said distant point for interrupting the current flow in said closed circuit to deenergize the second relay to permit said control relay to operate.

35. In combination, an electro-responsive 10 device, a circuit for said device, a trunk circuit, means for closing said circuits at substantially the same time, a relay energized over said trunk circuit to prevent said device from operating, and means at the distant end of said trunk circuit for stopping the flow of current therein to deenergize 15 said relay, whereby said device is operated.

36. In a telephone system, a control circuit extending to a distant point, means at the near end of said circuit for setting up a 20 current flow thereover, means at the distant end for stopping the current flow, a device at the near end responsive to such cessation of current flow, means at the near end for producing a series of interruptions in the 25 current flow prior to the operation of said means at the distant end, and means for preventing said device from responding to such series.

Signed by me at Chicago, Cook County, 30 State of Illinois, this 19th day of October, 1918.

JOHN WICKS.
